UNITED STATES PATENT OFFICE.

WILLIAM EVERETT VER PLANCK, OF ERIE, PENNSYLVANIA, ASSIGNEE TO GENERAL ELECTRIC COMPANY, A CORPORATION OF NEW YORK.

AIR-COMPRESSOR.

1,080,737.

Specification of Letters Patent.

Patented Dec. 9, 1913.

Application filed February 20, 1913. Serial No. 749,609.

To all whom it may concern:

Be it known that I, WILLIAM E. VER PLANCK, a citizen of the United States, residing at Erie, in the county of Erie, State of Pennsylvania, have invented certain new and useful Improvements in Air-Compressors, of which the following is a specification.

The present invention relates to air compressors and has for its object to improve and simplify their construction.

My improved compressor is of special value for use with internal combustion engines of the high compression type and will be described in this connection. When so used it supplies low pressure air for scavenging purposes and high pressure air for injecting fuel into the cylinder.

For a consideration of what I believe to be novel and my invention attention is directed to the following description and claims appended thereto.

In the drawings which illustrate one of the embodiments of my invention, Figure 1 is a view in vertical section of my compressor; Fig. 2 is an enlarged sectional view of the upper part of the compressor and the cooling means therefor, and Fig. 3 is a plan view of the same.

4 indicates the base of the compressor which may be of any suitable configuration. It may with advantage be a part of the engine frame as shown. Supported by suitable bearings therein is the crank shaft 5. To the crank 6 is attached a connecting rod 7, the upper end of which is connected by a pin to the tubular member 8 forming a part of the scavenging pump piston 9. The member 8 is guided in its vertical movements by the sleeve 10 which has a head 11 formed integral therewith that has a thickened peripheral portion or ring 12 that rests on and is supported by an internal shoulder 13 formed on the base. Between the ring and main portion of the sleeve are stiffening ribs 10. A second shoulder 14 lightly above the first is provided on the base and seated thereon is the scavenging pump cylinder or liner 15, said cylinder or liner being relatively thin and of substantially uniform cross-section to avoid weight and is removable from above. In the cylinder are segmental ports 16 and 17 through which air is admitted to the cylinder and after compression is delivered thereby to the low pres-

sure receiver 18, the latter supplying air to the working cylinders of the engine for scavenging purposes. The receiver is formed partially by integral walls of the base and partially by the cylinder 15, the upper and lower ends of which cylinder are seated pressure tight. As a general thing the working cylinders of the engine will be supported directly by the receiver and in line with the compressor so as to simplify the apparatus and so that the working pistons thereof can be directly connected to the crank shaft 5.

Situated at one side of the pump cylinder in any suitable or convenient place is a balanced piston valve 19 for controlling the ports 16 and 17. It is provided with upper and lower heads 20 and 21 that make sliding engagement with the walls of the annular openings in the partitions 22 and 23. Air is admitted to the interior of the piston valve through a screen 24 of any suitable construction. The valve is actuated by a link 25, lever 26 and eccentric 27 on the main shaft. The parts should be so timed and related that free air is admitted on one side of the piston 9 while it is being compressed on the other, the compressed air being delivered at the proper time to the receiver 18.

Situated above the base is a ring 28 that has a downwardly extending projection 29 which engages the top of the cylinder 15 and holds it in place. It also has an outwardly extending flange 30 that rests on the top of the base and is supported thereby. To the projection 29 is connected a head 31 which not only forms the upper head for the scavenging pump but also supports the low and high pressure cylinders of the compressor. The head is shaped to conform as closely as possible to the shape of the upper side of the piston 9 to reduce the cylinder clearance at this point. The lower head 11 is also shaped to conform to the shape of the under side of the piston and for the same reason.

Supported by the head 31 is the low pressure cylinder 32 and above that the high pressure cylinder 33, Fig. 2, said cylinders being in tandem relation. The low pressure piston 34 is or may be formed integral with the scavenging pump piston 9. In any event the two are mechanically and rigidly united. This arrangement has the double

- purpose of permitting all of the pistons to be driven by the same connecting rod and causing the piston 34 to act as a guide for the scavenging piston. Above the low pressure piston is a high pressure piston rigidly connected to it and working in the high pressure cylinder 33. All of the pistons and cylinders are in this manner accurately alined. By making the ring 28, projection 29, head 30 and cylinders 32 and 33 in one casting the structure as a whole is greatly simplified, the machine work more easily and accurately performed, and the number of parts reduced.
- 15 Air to be compressed is admitted to the low pressure cylinder by the conduit 35, Fig. 3, which leads from a suitable governor, such for example as that described in my pending application for Letters Patent, Serial No. 747,954 filed February 12, 1913. The air conduit is forked on its inner end and the branches 36 and 37 thereof feed air to the inlet valves 38 of which two are provided for each branch, all working in parallel.
- 20 Air is discharged from the low pressure cylinder by valves 39, also working in parallel, into the cooling coil 40 that surrounds the upper end of the cylinder and a part 25 of the high pressure cylinder. The valves 38 and 39 are contained in casings that are formed integral with the cylinder wall and are separated from each other to facilitate cooling. The cooling coil comprises an 30 inner and an outer set of turns that are connected in series. The upper turn of the outer set is connected to the head 41 of the high pressure cylinder and is admitted to said cylinder by suitable valve means. It is 35 discharged after compression and under valve control into the pipe 42 that extends between the cylinders and the coil 40 and connects with a cooling coil 43 which surrounds the low pressure cylinder. The lower 40 end of this coil is united by a coupling with an outlet conduit 44 located in the ring 28. The inlet conduit 35 for the air to be compressed also passes through the ring so that 45 all of the conduits are in substantially the same region. This facilitates the taking 50 down and assembling of the apparatus as will appear later. By extending the pipe 42 inside of the cooling coil 40 and between it and the cylinders, I am able to reduce the outside diameter of the apparatus. Further 55 since the pipe 42 is of smaller size than the coil 40 it can be more easily bent to the desired shape.
- Surrounding the cylinders and the cooling 60 coils is a dome shaped cover 45 which is shouldered to fit the ring 28. The joint between these parts should be water tight. At the top of the cover is a flanged conduit 65 for conveying cooling water to the interior of the cover so that all of the parts
- are submerged and therefore subject to the cooling action. Water escapes by the conduit 47 which purposely extends downwardly at 48 forming a siphon to enable the water to be siphoned out of the lower 70 part of the cooling chamber before taking off the cover. In the cover are one or more small rubber diaphragms 49 which while plenty strong enough to withstand the water pressure will be blown out if by chance one 75 of the cooling coils ruptures. Without some such device there would be danger of the whole cover being disrupted unless made unduly heavy because the pressure in the high pressure cooling coil is often as high 80 as 1000 pounds per square inch. The high pressure air leaving by the conduit 44 passes through a safety valve 50, Fig. 1, of suitable construction carried by a fitting attached to the ring 28. From the fitting are pipes 85 51 extending to the fuel injectors of the engine.
- It will be seen by breaking the joint of conduit 46 and draining off the cooling water that the cover can be removed exposing the coils and also the screw threaded 90 plugs over the various valves, said valves being arranged on a smaller diameter than the inner series of coils. As before stated all of the air inlet and discharge conduits 95 are arranged in the ring 28 so that they do not have to be disturbed in order to get at the interior parts. Since the cylinders and valve casings as well as the cooling coils are all exposed to the action of the cooling 100 water I am able to get the maximum cooling effect with an apparatus of moderate size. All of the parts are simple in construction and of a character not liable to get out of order.
- In accordance with the provisions of the 105 patent statutes, I have described the principle of operation of my invention, together with the apparatus which I now consider to represent the best embodiment thereof; but 110 I desire to have it understood that the apparatus shown is only illustrative, and that the invention can be carried out by other means.
- What I claim as new and desire to secure 115 by Letters Patent of the United States, is:
1. In an apparatus of the character described, the combination of a base containing a receiver, a removable cylinder located therein which forms a wall of the receiver 120 and has ports communicating therewith, valve means controlling the ports, heads for the cylinder that are supported by the base, one of which holds said cylinder in place, a piston in the cylinder, a member carried by 125 the piston which is guided by one of the heads, a driving shaft, and connections between the shaft and the valve means and pistons for actuating them.
  2. In an apparatus of the character de- 130

scribed, the combination of a base containing a receiver and having internal shoulders, a removable cylinder that rests on one of the shoulders, a head that rests on the other and supports a tubular guide, a second head that rests on the base and holds the cylinder in place, a piston in the cylinder, a member carried thereby which moves in the guide and is attached to the piston, a driving shaft, and a connection between the shaft and piston.

10 3. In an apparatus of the character described, the combination of a base having shoulders, a cylinder that is supported by one of the shoulders, a head therefor which is supported by another shoulder, a guide that is carried by the head, a piston, a member moving with the piston and engaging the guide, a second head for the cylinder that carries a second cylinder, a piston for the second cylinder that is connected to the first and in addition to acting as such forms a guide for the first piston, a driving shaft, and a connecting rod means between the shaft and the pistons.

25 4. In an apparatus of the character described, the combination of a base containing a receiver, a cylinder therein which forms a wall of the receiver, ports in the cylinder, a valve that controls the admission of fluid to the cylinder and its passage therefrom to the receiver, means for actuating the valve, a piston in the cylinder, guides on opposite sides of the piston, heads for the cylinder that are directly supported by the base and also receive and direct the movements of the guides, a main shaft, a connection between the piston and the shaft, and means actuated by the shaft for moving the valve.

30 5. In an apparatus of the character described, the combination of a base, a ring supported thereby, a cylinder supported by the ring, conduits for conducting fluid to and from the cylinder that pass through the ring, a cover that rests on the ring and incloses the cylinder, a piston in the cylinder, a driving shaft, and connecting means between the piston and shaft.

35 6. In an apparatus of the character described, the combination of a base, a ring supported thereby, a cylinder, a head carried by the ring which supports the cylinder and forms one wall of a cooling chamber, conduits for conducting fluid to and from the cylinder that pass through the ring, a cover supported by the ring that covers the cylinder and forms with the ring and head a chamber which is adapted to contain a cooling fluid, a piston for the cylinder, a driving shaft, and means connecting the shaft and piston.

40 7. In an apparatus of the character described, the combination of a base, a ring supported thereby, a cylinder that is supported by the ring, a cooling coil that surrounds the cylinder, a conduit conveying

fluid to the cylinder that passes through the ring, a conduit connected to the coil that also passes through the ring, a cover that surrounds the cylinder and coil and rests on the ring, a piston in the cylinder, a shaft, and a connection between the shaft and the piston.

45 8. In an apparatus of the character described, the combination of a base, a ring supported thereby, cylinders arranged in tandem relation which are supported by the ring, a conduit that passes through the ring for admitting fluid to one of the cylinders, a cooling coil that is connected to and surrounds said cylinder and conveys fluid therefrom to the other cylinder, a second cooling coil that is connected to the second cylinder and conveys fluid therefrom, a conduit that passes through the ring and is connected to the second coil, a cover for the cylinder and coils, pistons for the cylinders, a shaft, and means for uniting the pistons and shaft.

50 9. In an apparatus of the character described, the combination of a base, a ring supported thereby, low and high pressure cylinders arranged in tandem relation, a head for supporting the cylinders which is carried by the ring and forms a wall of a cooling chamber, cooling coils that convey fluid from the low to the high pressure cylinder and also convey it from the high pressure cylinder, conduit means that pass through the ring and convey fluid to the low pressure cylinder and receive it from the high pressure cooling coil, a cover that incloses the cylinders and coils and cooperates with the ring and head to form a liquid containing chamber, conduits for conveying liquid to and from the chamber, pistons for the cylinders, a shaft, and means for uniting the shaft and pistons.

55 10. In an apparatus of the character described, the combination of a base, cylinders arranged in tandem relation which are supported thereby, a cooling coil for conveying fluid from one cylinder to the other which comprises inner and outer sets of turns that surround the cylinders, a second cooling coil that is connected to the high pressure cylinder and surrounds the low pressure cylinder, a conduit connecting it with its cylinder which passes through the low pressure cooling coil, an inclosure for the cylinders and coils, means conveying liquid to and from the inclosure, pistons for the cylinders, a shaft, and means connecting the shaft and pistons.

60 11. In an apparatus of the character described, the combination of a base, a ring mounted thereon, a cylinder, a head supported by the lower part of the ring which carries the cylinder, a cover that covers the cylinder and rests on the ring, said cover and ring forming a chamber adapted to contain liquid, a conduit in the cover for admitting liquid, and a conduit made in the form of a

siphon that is carried by the ring for removing liquid from the chamber and ring.

12. In an apparatus of the character described, the combination of a base, a pump cylinder mounted therein, a ring that rests on the base, a head for the cylinder and low and high pressure cylinders that are formed integral with the ring, pistons for the cylinders, a shaft, and means connecting the shaft and pistons.

13. In combination, a removable scavenging pump cylinder, low and high pressure cylinders, all of said cylinders being ar-

ranged in axial alignment, a base, a means that holds the scavenging pump cylinder in place and also supports the low and high pressure cylinders, pistons for all of said cylinders that are mechanically united, a shaft, and a connecting rod, means that unites the shaft and all of said pistons.

In witness whereof, I have hereunto set my hand this 18th day of Feby. 1913.

WM. EVERETT VERN PLANCK.
